ELECTRIC PLUG CONNECTER

Nathan Chirelstein, Newark, N. J.

Application August 4, 1934, Serial No. 738,397

2 Claims. (Cl. 173—361)

This invention relates to electric plug connectors and refers more particularly to portable attachment plugs adapted to be inserted in a socket connected to an electric current supply line for the purpose of connecting an electrical apparatus with said electric current supply line.

An object of this invention is the provision of a plug connector comprising contact prongs of such shape that they hold or lock a closure plug situated between the contact prongs and adapted to be inserted into a suitable opening formed in the main body of the plug connector.

Another object of this invention is the provision of a plug connector consisting of a few parts of relatively simple construction, which may be easily assembled in a short time.

Another object is the provision of a plug connector which can be quickly and conveniently manufactured at a low cost.

The above and other objects of this invention may be realized through the provision of a plug connector comprising a main body member carrying a closure plug, the contact prongs of the plug connector being provided with projections or lugs holding or locking the closure plug, and also being provided with other projecting portions clamping the prongs and the closure plug within the main body member.

The invention will appear more clearly from the following detailed description when taken in connection with the accompanying drawing showing preferred embodiments of the inventive idea.

In the drawing:

Figure 1 shows a plug connector in side elevation.

Figure 2 is a vertical section through the plug connector.

Figure 3 is a section along the lines 3—3 of Fig. 2.

Figure 4 is a sectional view, showing the plug connector while it is being assembled.

Figure 5 shows one of the contact prongs.

Figure 6 is a perspective view of the closure plug.

Figure 7 shows a contact prong of a somewhat different form.

The plug connector illustrated by way of example in Figures 1 to 4 of the drawing, comprises a main body member 10 preferably made of a resilient insulating material, such as rubber or the like, and comprising a preferably cylindrical portion 11 having a corrugated flange 12, and a tapered end portion 13.

Central openings 14 and 15 are formed in the tapered end portion 13 and the cylindrical body

11, respectively. The opening 14 is preferably round in cross-section, while the opening 15 may be rectangular in shape and is flanked by two sockets 16 and 17 extending into the tapered end portion 13 and forming grooves 18 and 19. Pockets or recesses 20, 21, 22 and 23 are formed in the walls of the opening 15, the pocket 22 being situated opposite the pocket 20, while the pocket 23 is situated opposite the pocket 21.

A closure plug 24 fitting into the rectangular opening 15 is shown in Figure 6 of the drawing. The closure plug 24 which in the example illustrated, has four flat side surfaces 25, 26, 27 and 28, also may be made of resilient insulating material, such as rubber, or it may be made of a hard insulating material. If the main body member 10 consists of rubber or the like, the closure plug 24 should, preferably, be made of hard insulating material. On the other hand, if the main body member consists of a hard insulating material, the closure plug must be made of an elastic material, such as soft rubber or the like.

As shown in Figures 2, 4 and 5, the closure plug 24 is preferably provided with an opening or hole 32 formed in the side surface 26 and a similar hole 33 formed in the opposite surface 28 of the plug.

The lower portion of the closure plug 24 is provided with four projecting walls 34, 35, 36, and 37, which are interconnected by means of an intermediate web 38.

The web 38 and the walls 34 and 35 form a chamber or recess 39 while a similar chamber 40 is formed by the web 38 and the walls 36 and 37 at the opposite side of the closure plug 24.

The contact prongs 41 and 42, one of which is shown in Figure 5 of the drawing, are similar to each other in shape and serve for conducting the electrical current. Each prong comprises a main blade portion 43, having an oval opening 46 which may be formed in the upper end of the blade.

As shown more clearly in Figures 2 and 5, a lug or a projection 48 is cut out of the middle portion of the blade 43 and is bent in a direction away from the closure plug 24, thereby forming an opening 49 in the plate 43. The projection 48 forms an acute angle with the blade 43 and is used for clamping the prong within the main body member 10, as will be described more fully hereinafter.

Another projection 50 is cut out of the blade 43 somewhat below the projection 48. The projection 50 which is adapted to be inserted into one of the openings 32 or 33 of the closure plug

24, is bent at right angles to the blade 43, thereby forming an opening 51 in the blade. Another preferably round or oval opening 52 is provided below the opening 51, close to the lower end 53 of the contact prong.

5 The conductor cord 54 used for transmitting the electrical current from the contact prongs 41 and 42 to an electrical apparatus comprises a tubular sheathing containing a pair of conducting 10 wires 55 and 56 surrounded by insulation 57 and 58, respectively.

15 The end 59 of the conducting wire 55 is passed through the opening 52 of the contact prong 41 and is then passed through the opening 51 of the same prong and pressed against the adjacent wall of the blade portion 43. Thus the end 59 is bent in the form of a hook and is firmly connected with the contact prong 41.

20 The end 60 of the conducting wire 56 is passed in the same manner through the openings 52 and 51 of the contact prong 42 and is then pressed against the adjacent wall of the contact prong 42, whereby a permanent electrical connection is established between the wire 56 and the contact 25 prong 42.

25 The contact prong 41 is connected with the closure plug 24 by inserting the projection 50 of the contact prong 41 into the corresponding opening 32 formed in the closure plug 24. The contact prong 42 is connected with the closure plug 24 by inserting its projection 50 into the opening 33. This arrangement is shown more clearly in Figure 4 of the drawing. The ends of the insulated wires are situated within the recesses 39 and 40 of the plug 24. The ends 59 and 60 of the wires 55 and 56 are pressed against the edges of the openings 51 of the prongs 41 and 42 by the edges 61 and 62 of the plug 24. Due to this arrangement, a permanent contact is maintained 40 between the wires 55 and 56 on the one hand and the contact prongs 41 and 42 on the other hand, while at the same time the prongs 41 and 42 are firmly connected with the closure plug 24.

45 In some cases it may be advisable to solder the ends of the connecting wires to the contact prongs although as a rule a sufficiently stable connection is formed by passing the wires through the two openings 52 and 51 and by the pressure of the adjacent edges of the closure plug 24.

50 The final step in assembling the plug connector is accomplished by inserting the closure plug 24 into the corresponding opening 15 formed in the main body member 10, by moving the closure plug 24 downward from the position shown in Figure 55 4 into the position shown in Figure 2.

55 During the insertion of plug 24, the contact prongs 41 and 42 slide within the sockets 16 and 17 until the ends 53 of the contact prongs 41 and 42 come to rest at the bottom of the grooves 18 and 19, respectively; the projections 48 are pressed against the blade portions 43 until they reach the recesses 22 and 20. Then these projections 48 assume the position shown in Figure 2, pressing against the walls of the recesses 22 and 20, and thus providing a permanent connection between the prongs 41 and 42 and the plug 24 on the one hand, and the main body member 10 on the other hand.

70 Due to this arrangement, the projections 48 remain in contact with the adjacent walls of the recesses 22 and 20, preventing a separation of the plug 24 from the main body member 10, when the plug connector is pulled out of a socket. On the other hand, due to the provision of projections 75 59 fitting into the openings 32 and 33, the con-

tact prongs 41 and 42 will not slide with respect to the main body member 10 when the plug connector is inserted into a socket.

As shown in Figure 2, the ends 59 and 60 of the conducting wires 55 and 56 are situated in the recesses 23 and 21, respectively, which are formed in the main body member 10. At the same time the two conducting wires are separated from each other by the web 38.

The contact prong 29 shown in Figure 7 of the drawing comprises a blade 30 having an opening 63 formed at the lower end of the blade and adapted to hold an end of a conducting wire. A lug or projection 44 which is similar to the projection 48 shown in Fig. 5, is cut out of the 15 middle portion of the blade 30, thereby forming an opening 45 in the blade. The projection 44 is adapted to come in contact with a wall of one of the recesses formed in the main body member. Another projection or lug 31 is situated 20 at the opposite side of the blade 30 and is also cut out of the blade, whereby an opening 47 is formed in the blade 30. The projection 31 forms an acute angle with the blade 30, so that it holds the closure plug by being forced into a soft 25 rubber closure plug thereby holding it in place.

What is claimed is:

1. In a plug connector comprising a main resilient body member and a closure plug positioned within said main resilient body member; a contact prong comprising a substantially straight elongated blade portion, a substantially rectangular cut-out projection integral with said blade portion; the width of said projection being smaller than that of said blade portion, a rectangular opening being formed in said blade portion adjacent said projection, an edge of said rectangular opening being integral with an edge of said projection, said projection extending at an acute angle in relation to said blade portion, and another substantially rectangular cut-out projection situated under the first-mentioned projection and integral with said blade portion, the width of the second-mentioned projection being smaller than that of said blade portion, a rectangular opening being formed in said blade portion adjacent the second-mentioned projection, an edge of the second-mentioned opening being integral with an edge of the second-mentioned projection, the second-mentioned projection extending at a substantially right angle in relation to said blade portion, the first-mentioned projection holding said body member, the second-mentioned projection holding said closure plug. 50

2. A plug connector comprising a main resilient body member having a central opening, another central opening forming a continuation of the first-mentioned opening, the two central openings extending through the entire body member, and at least two recesses formed one over 60 the other in the walls of the first-mentioned central opening; a conducting wire situated in the second-mentioned central opening, a resilient closure plug fitting into the first-mentioned central opening, and a contact prong comprising 65 a substantially straight elongated blade portion, a substantially rectangular cut-out projection integral with said blade portion; the width of said projection being smaller than that of said blade portion, a rectangular opening being 70 formed in said blade portion adjacent said projection, an edge of said rectangular opening being integral with an edge of said projection, said projection extending at an acute angle in relation to said blade portion, and another sub- 75

stantially rectangular cut-out projection situated under the first-mentioned projection and integral with said blade portion, the width of the second-mentioned projection being smaller than that of said blade portion, a rectangular opening being formed in said blade portion adjacent the second-mentioned projection, an edge of the second-mentioned opening being integral with an edge of the second-mentioned projection, the second-mentioned projection extending at a substantially right angle in relation to said blade portion, the

first-mentioned projection being situated in one of said recesses and pressing against a wall thereof to hold said body member, the second-mentioned projection being situated in an opening formed in an adjacent wall of said closure plug 5 to hold the same, an end of said conducting wire passing through the second-mentioned rectangular opening and being situated in the other one of said recesses.

NATHAN CHIRELSTEIN. 10
